UNITED STATES PATENT OFFICE.

HENRY W. O'NEILL, OF ELMHURST, NEW YORK, ASSIGNOR TO WESTERN ELECTRIC COMPANY, INCORPORATED, OF NEW YORK, N. Y., A CORPORATION OF NEW YORK.

TELEGRAPH SYSTEM.

Application filed August 8, 1925. Serial No. 48,949.

This invention relates to telegraph systems, and more especially to telegraph systems wherein alternating currents of audio frequency are employed for signalling.

5 An object of the invention is to provide an efficient and highly economical alternating current telegraph system, utilizing currents of audio frequency.

10 A feature of the invention relates to an alternating current telegraph system in association with circuits where relatively low potential levels may not be exceeded, and wherein special relays are employed for directly converting alternating current telegraph signals into continuous current signals.

20 Another feature of the invention relates to a telegraph system employing carrier currents within the voice frequency range, in conjunction with so-called "acceleration" type relays as detectors and filters.

25 A further feature relates to an alternating current telegraph system wherein short-circuiting vibrators are employed as sources of alternating currents.

An additional feature relates to current producing devices which may normally be inert but automatically rendered responsive to the transmission of signals.

30 A still further feature relates to an arrangement for employing guard or "pilot" current with a telegraph line during non-transmission periods.

35 Another feature relates to a high-speed direct current telegraph system which is composited with, and rendered operable by the present alternating current system.

40 Referring to the drawing, Fig. 1 shows loop circuits comprising sending and receiving legs S and R terminating in a telegraph switchboard TS, at a central office.

45 Fig. 2 shows other portions of the switching equipment which includes apparatus for monitoring and communicating from the switchboard.

50 Fig. 3 to the left of the broken line shows a number of transmitting channels T¹, T², etc., with associated alternating current circuits. This portion of the figure also shows in detail a first receiving channel RC¹, and a second similar receiving channel RC². The portion of Fig. 3 to the right of the broken line represents transmitting and receiving equipment at a distant office which equip-

ment may be similar to that shown in Figs. 55 1 and 2, in the left-hand portion of Fig. 3 and in Fig. 6.

Fig. 4 shows the manner in which a two conductor line may be "duplexed" by means of balancing coils, and composited with a 60 high-speed ground return Morse duplex system.

Fig. 5 shows the manner in which a metallic Morse system may be combined with the duplex line of Fig. 4 in substitution of 65 the grounded Morse equipment; while Fig. 6 shows in abbreviated form equipment which may correspond with the equipment of Figs. 1 and 2.

Figs. 1, 2 and 3 of the drawing when arranged with Fig. 2 above Fig. 1, and Fig. 3 to the right of Fig. 1, show in sufficient detail such portions of a telegraph system as may be necessary to a clear understanding of one form of carrying out the invention. 70

For convenience of description, the system may be divided into an alternating current portion and a direct current portion. The alternating current circuits, for transmitting, comprise carrier current supply 80 sources which may be formed of vibrators preferably of the short-circuiting type, as shown, with means for controlling the application of such currents to a main line. For receiving such currents, suitable relays, 85 preferably of "acceleration" type, as shown, serve as detectors and filters in separating the several carrier currents according to frequency, and in translating them into direct current signals. The direct current circuits 90 currents at a receiving point may be re-perform two main functions. The outgoing carrier currents may be controlled by the ordinary Morse telegraph signals from a transmitting device, while in turn, the Morse 95 signals resulting from the incoming carrier peated into a "loop", or other telegraph circuit by means of relays of the "acceleration" type.

100 In a general description of the system, a main line EL (Fig. 3) may transmit carrier current signals in one direction, while a main line WL may serve for transmission in the opposite direction. The lines EL and WL may be the usual telephone lines with 105 associated repeater apparatus. A plurality of transmitting channels T¹, T², etc., and a plurality of receiving channels RC¹, RC²,

etc. serve to join a plurality of Morse telegraph equipments with the main lines.

Each Morse extension may comprise a sending leg and a receiving leg. For example, the extensions shown in detail in Fig. 1, comprise sending leg 101 and receiving leg 102. Similarly, the extensions shown in Fig. 6 comprise a sending leg 103 and receiving leg 104. It will be understood that other Morse extensions similar to 101 and 102 may be provided as required. The switching devices (Fig. 2) provide that the circuits may be conditioned for either full duplex or for half duplex working at a terminal or substitution as will presently appear. Associated with each line there is a conventional monitoring and supervisory control circuit also shown in Fig. 2.

In association with each of the sending and receiving legs, there is respectively provided a transmitting and a receiving channel. Each transmitting channel is supplied with carrier current of a particular frequency. The carrier frequencies are so chosen as to be odd multiples of a basic frequency which for convenience will be referred to as a frequency f^1 . The lowest frequency employed in the present system is the fifth multiple of this frequency and will therefore be referred to as a frequency f^5 . Each carrier frequency is allotted a range of $f^1 \times 2$ and therefore is separated from the limits of the two adjacent frequencies by a frequency corresponding to the frequency f^1 cycles above and f^1 cycles below its own nominal frequency.

The carrier frequency generating means comprises short-circuiting vibrators 311, 312, etc., which may be mechanically tuned, as well as electrically tuned with a circuit comprising the windings of a transformer such as the unit 301. The primary winding of this transformer may be tuned by means of a condenser 321, while the secondary may be tuned by a condenser 333. Ordinarily, no additional filtering equipment in the carrier generator circuit will be necessary, since it is an inherent characteristic of short-circuiting vibrators that the resulting wave form is comparatively smooth and free from sharp current effects.

Individual to each receiving channel RC^1 , RC^2 , etc. is a receiving relay 304, 306, etc. These relays are preferably of the so-called "acceleration" type such as shown and described in U. S. patent granted to H. W. O'Neill, Nov. 23, 1926, 1,607,910.

As described in the above mentioned patent, the acceleration type relays consist of an armature capable of vibrating adjacent the poles of an electromagnet which is adapted to be energized by alternating current. The armature carries a sealed chamber wherein a so-called "loose" contact assembly is provided. The armature is furthermore

adapted to be mechanically tuned to any desired frequency. When a suitable alternating current is sent through the windings of such a relay, the resulting vibratile effect of the armature causes the normally closed contacts within the sealed chamber to separate, while on cessation of the current the contacts may close. In addition to being tuned mechanically, these relays may also be tuned electrically by means of condensers as condenser 305. Due to the extreme sensitivity and selectivity of the receiving relays, a comparatively large number of different carrier frequencies may be transmitted over a main line, without exceeding the usual voltage levels permissible in the circuits of a telephone plant. Furthermore these receiving relays are substantially unaffected by inductive surges and will not translate signals other than those formed by impulses composed of a stream or succession of waves of the particular frequency to which the receiving relay may be tuned. Because of this latter feature, the receiving relays permit the superposing of alternating currents over circuits operated with direct currents, either on the metallic Morse, or the ground return Morse principles.

A direct current polar duplex circuit is formed by a "sending" relay 106 and a "break" relay 109, both of polarized type. The left windings of these relays connect to an artificial line represented by a resistance 204, while the right windings connect over the loop circuit 101, to positively-poled grounded battery. The apex of the duplex circuit, formed by the junction of the windings in the differentially connected current meter 110, is connected by way of a jack 202 to negatively poled battery. In conventional manner, the greater energy through the right, or "line" windings of the relays 106 and 109 normally stresses the armatures of these relays to their "marking" contact stops, as shown. The reference characters S and M have, for convenience, been employed to respectively indicate the spacing and marking contacts of the various line-controlled relays of this system.

In the present system the equipment at the East office shown to the right of the broken line of Fig. 3 may be in duplicate of the equipment at the West office, where the circuits are fully shown in diagrammatic form. Therefore, in avoiding unnecessary duplication, the rectangle 361 and circle 371 may be understood as inclosing receiving equipment under control of the transmitting equipment formed of T^1 (Fig. 3), and the transmitting portion of Figs. 1 and 2. This receiving equipment may correspond with that formed by the relay 304 and the receiving portion of the equipment of Figs. 1 and 2. This transmitting and receiving equipment forms a first channel over the east line 130

circuit EL. Over this line a second frequency channel is formed by transmitting equipment T² and a portion of Fig. 6 working into receiving equipment within 362 and 372. A west line WL has a first frequency channel formed of transmitting equipments 367, 377, working into receiving equipment formed of relay 304 and the receiving portion of Figs. 1 and 2, while a second frequency channel over this line, comprises transmitting equipment 368, 378, working into receiving equipment comprising relays 306 and the receiving portion of Fig. 6.

Within a rectangle 323 is shown transmitting pilot equipment for the east line EL which controls receiving equipment which may be assumed as present at 363. For the west line WL, pilot transmitting equipment 373 serves for control of receiving equipment 353. The receiving equipment at 363 may correspond with that at 353, while the transmitting equipment at 373 may correspond with the transmitting equipment at 323.

From the foregoing it will be clear that the circuit EL, with the circuit WL, may constitute a so-called four-wire system, in which a circuit of two conductors may carry transmission for a plurality of channels in one direction, while a second two-wire circuit serves reciprocally for carrying transmission for a plurality of channels in the opposite direction.

In taking advantage of the inherent sensitivity and selective characteristics of the present "acceleration" type relays, a single two-wire line circuit may, when desirable, be employed in substitution of a four-wire circuit system for carrying impulses for channels in which the transmission may be in opposite directions. To render this readily understood in connection with the present disclosure, the equipment of Fig. 4 may be substituted for the equipment at the East station. For this purpose, line EL and line WL may respectively connect to the correspondingly indicated conductors of a balancing coil 401 which forms a metallic duplex arrangement for a two-wire main line ML. A balancing coil 402 at the opposite end of this line may, in turn, branch to a second four-wire line section, or the conductors of the receiving side and those of the transmitting side may be respectively joined to receiving and transmitting equipments as present at the East station of Fig. 3.

The characteristic of the present "acceleration" type relays concerning their immunity to relatively slow moving current impulses, which characterize the highest speeds of direct current telegraphs as compared with the order of the frequencies employed in the alternating current portions of the present system, render it possible to composite the line ML with direct current

telegraphs without employing the usual inductance and capacity units for smoothing the direct current impulses. In turn, the ordinary direct current telegraphic devices are immune to the low potential high frequency alternating currents of the present system, therefore, ground return telegraph system as shown, may also be employed with the line ML. As well understood, in the telegraph art the reactances employed for smoothing the impulses in former composited circuits affect to a marked degree the speed at which signalling may be carried on over such direct current telegraph circuits. The features of the present system as already pointed out whereby the impulse smoothing reactances may be dispensed with, is of importance from the standpoint of reduced cost for equipment, and affording a gain in message capacity of a channel due to the higher speeds of sending which may be employed over the direct current channels.

The foregoing features relative to composited circuits also apply to superimposed direct current working on the metallic Morse basis. For this, the arrangement of Fig. 5 may be substituted for the arrangement of Fig. 4, thereby providing that in addition to simultaneous east and west working of alternating current channels over the line section ML, a metallic or two-wire direct current duplex telegraph system may also be operated over this line.

In a more detailed description of this system, let it be assumed that a key 201 is operated to its alternate position, a "battery" key 206 is operated to the right, while the keys 203, 205, and 207 may be in their normal positions. The circuits are thus arranged for full duplex working at the substation served by the loops S and R, a plug 121 being inserted into a jack 122, while a plug 123 may be inserted in a jack 124. Messages may now be sent over leg 101, and other messages received over leg 102 simultaneously. For the loop 101, the circuit is from negative battery through contacts of jack 202, contacts of key 201 in operated position, conductor 251, right-hand windings of current meter 110 and relays 106 and 109, conductor 152, contacts of key 203 in normal position, conductor 252, inner back contacts of relay 111, conductor 153, contacts of key 205, conductor 254, left winding of relay 113, through the closed loops, and returning to positive battery through the right winding of relay 113.

An open position of the key 108 disconnects the circuit through the right windings of relays 106 and 109, and the armatures of these relays may then move to their spacing contacts under energy in the circuit which extends from ground through the artificial line resistance 204, normal contacts of key 203, conductor 151, left wind-

ings of the relays 109, 106 and meter 110 to grounded negative battery at the jack 202. When the armature of relay 106 leaves its marking contact the relay 331 releases, 5 and over obvious circuits, effects response of a short-circuiting vibrator 311. A relay 341 may also be under response at this time in disconnecting the pilot current equipment as presently will be described. Under 10 operation, the contacts of vibrator 311 set up changes of battery current in the primary winding of a repeating coil 301, and thus produce an alternating current of definite frequency as determined by the mechanical and electrical adjustments of vibrator 311. In this case, the particular frequency to which the vibrator is adjusted, causes the generation of an alternating current of frequency f^5 . The secondary of 15 transformer 301 is connected to the line EL so long as the armature of relay 106 is on its spacing contact. After traversing the line EL the alternating current effects response of a relay tuned to respond only to 20 the frequency f^5 . When the key 108 is closed the armature of the relay 106 moves to its marking contact, thereby disconnecting the secondary winding of the transformer 301, and removing the alternating 25 current from the line EL.

The relay 331 is of a slow-to-operate type so that its armature may remain against its back contact so long as relay 106 may be responding to message impulses, and in turn 30 the relay 341 is of a slow-to-release type thus insuring that the pilot current equipment may continue disconnected during message sending.

It will be obvious that each time key 108 35 is opened to send a spacing signal, the secondary winding of transformer 301 will be connected to apply the carrier current to line EL. While each time a marking impulse is transmitted, by key 108 being closed, the armature of relay 106 will be 40 positioned to disconnect the alternating current from the line. In this way the direct current telegraph impulses are converted into alternating current impulses to 45 control distant receiving relays.

For convenience in describing reception 50 on the equipment at 361, 371, of the signals from the key 108 let it now be assumed that such signals may be under transmission from the equipments 377, 367 to be received by way of alternating current relay 304 and direct current relay 112, in controlling a receiving device or sounder 114. The circuit for this polarized sounder is from 55 positive grounded battery, right-hand winding of relay 119, jack 124, and plug 123, sounder 114 in the loop R, returning over the left-hand winding of the relay 119, conductor 159, left-hand normal contacts of 60 key 207, conductor 257, contacts of key 205,

conductor 258, outer back contacts of relay 111, conductor 161, right-hand normal contacts of key 207, upper contacts of key 201, conductor 259, armature and marking contact of relay 112, conductor 154, contacts of 65 key 206, to grounded negative battery, by way of jack 209. When a spacing signal is received over line WL, the contacts of relay 304 are opened and relay 112 releases its armature to the spacing contact. Thereupon 70 the positive grounded battery by way of the contacts of jack 208, is substituted for the negative battery at jack 209, and the sounder 114 will indicate a spacing signal. For a marking signal, cessation of 75 alternating current in the channel RC¹ of the line WL, permits restoration of relay 304. Relay 112 then responds to close its marking contacts thereby switching the 80 loop circuit 102 back to the negative battery at jack 209, thus causing the sounder 85 114 to indicate a marking signal.

From the foregoing description it will be clear that signals originating at the key 108 90 may control the generation and application of alternating current to the line EL, which may be translated by receiving devices at equipments 361, 371. And further, that in a similar manner, impulses originating at 95 377, 367, may control the generation and application of alternating current impulses to the line WL whence these impulses may become effective through the full-duplex equipments of Figs. 1 and 2, and be manifested on the receiver 114.

In describing the operation of the pilot channel let it now be assumed that all message channels of the line EL may be idle. The respective relays 331, 332, etc., of the different channels will therefore stand operated over circuits respectively corresponding with the circuit already described for the relay 331. A "bus" conductor 352 will thus stand entirely disconnected from grounded battery, thereby permitting de-energization of the slow-to-release relay 341. This closes an obvious circuit for energizing a short-circuiting vibrator 342 from grounded battery in parallel with the primary winding of a transformer 343. The reed armature of this vibrator may be tuned to a frequency differing from the frequencies of the associated message channels. This vibrator may operate in the same manner as that already described for the vibrator 311 except that under closure the contacts of the vibrator short-circuit the primary winding of the transformer 343 in addition to short-circuiting the winding of the vibrator. Such current changes in the transformer 115 343 induce alternating current in the secondary winding. Over an obvious circuit which includes a suitable current indicating device or meter 351 these induced currents may reach the line circuit EL. At the East sta- 120 125 130

tion a relay of acceleration type, tuned to respond to the particular frequency of the pilot current may be present at the point 363, for translating or indicating the presence of this guard current.

For convenience in describing the reception of the pilot current let it now be assumed that under an idle condition of all message channels on the line WL transmitting pilot equipment corresponding with the pilot equipment 323 at the West office may be present and under operation at the point 373 at the East office. At the West office a relay 344 of acceleration type similar to the relays 304 and 306, but tuned to respond only to the frequency of the pilot current, is connected in bridge of the line WL. Under pilot current this relay responds to disconnect the left-hand winding of a current meter 345, whereupon, current from battery by way of the winding of relay 112 and contacts of the relay 304 and the right-hand winding of the meter 345 causes a deflection to the right. This meter may form part of the supervisory equipment of Figs. 1 and 2. The general purpose of the pilot current is to provide a definite indication as to the continuity of the line and to warn against irregularities or faults which may occur during idle or non-message periods. At the inward or receiving end of the circuit, the meter 345 of the channel RC^1 may serve as the pilot current indicating means, while at the outward end a suitable meter as the meter 351 may be employed to indicate whether, and in what quantity pilot current may be flowing outward to a line circuit.

When message signals may be under transmission over the line WL, a relay at the East office which may correspond with the relay 341 at the West office, will stand in its operated position in a manner similar to that already described for the latter relay. This serves to disconnect the pilot current equipment, whereupon relay 344 may restore and thus reestablish energy in the left windings of the meter 345. Assuming now that the message signals just mentioned may be for the channel RC^1 , response of the relay 304 will disconnect the right winding of the meter 345 which may then deflect to the left under current in the left winding as present by way of the contacts of the relay 344.

Each channel may be provided with a meter similar to the meter 345 and the contacts of the pilot relay 344 may be connected in common to all meters, as indicated, by the conductor in half-tap from the conductor 347. Ordinarily, however, the pilot current relay may be connected to a single meter as shown, and in addition to this meter serving to indicate the presence of message impulses on the associated channel,

it may also indicate the absence of any message signals on the line, and the presence of the pilot current, or circuit checking energy.

It may be pointed out that the term "pilot" has been applied to the present line checking current merely as a matter of convenience of description, and it is to be understood that the scope of the present use of such current and signals may not be limited or affected by other uses in signal and power systems in connection with which the term pilot current, pilot lamps, etc., may also be employed.

From the foregoing description, it will be clear that a continuous indication is given of the condition of the main lines EL and WL, and of the several receiving channels RC^1 , RC^2 , etc., regardless of whether message signals may be under transmission.

The feature of the present system which relates to the small amount of signalling energy required during operation on the channels T^1 , T^2 , RC^3 , RC^4 , etc., renders it possible to use a two-conductor line for transmission in opposite directions without interference or danger of exceeding the limits of the low potential levels to which signalling in the telephone plant must be restricted.

Referring to Fig. 4, there is shown one arrangement in which a four-conductor line, such as, for example the line EL, WL of Fig. 3, may be combined with a ground return Morse system. The line EL, WL is preferably "duplexed" by means of the balancing coils 401 and 402 with their associated artificial line networks AL_1 and AL_2 respectively. For this purpose the valancing coil 401 may be inserted at the West office in the four-conductor line of Fig. 3 at the section included within the dotted rectangle 374. Similarly, coil 402 at the East office may be inserted in the line at the section included within the dotted rectangle 375, the lines EL and WL now being dispensed with. By means of this arrangement transmission may be carried on between East and West offices by means of the two-conductor line ML. Accordingly, alternating current signals impressed on conductors EL as a result of the manipulation of a key similar to key 108 will in turn be impressed on line ML by means of windings 411 and 412 of the coil 401. As well understood in the telephone art, these signals will have no effect on the conductors WL. These currents on line ML may in turn flow through the winding 413 of balancing coil 402 and induce similar currents in winding 414. The conductors "Receiving" connected to the winding 414 may lead through receiving apparatus represented schematically at 361 and 371.

For the transmission of messages from the East office, sending equipment 368 and 378

may be actuated to cause the impression of alternating current signals on the channel conductors T^1 which, as already noted, may be connected with the conductors "Transmitting" which are now assumed as joined to the windings 415 of coil 402. Alternating current signals will therefore be impressed on line ML by means of windings 415 and 416, the windings 413 and 414 being unaffected by these currents. The currents in line ML will correspondingly induce currents from the windings 417 into windings 419 of coil 401. The signals thus received over conductors WL as already noted, may effect response of the proper one of the relays 304, 306, etc., to cause these signals to be translated into corresponding direct current signals to control receiving equipment as shown in Figs. 1 and 2.

As already pointed out, the small amount of energy required to actuate the receiving relays 304, 306, etc., and their relative unresponsiveness to current surges render it possible to superpose a ground return Morse telegraph system on each conductor of the line ML, already duplexed for alternating currents, without insertion of the usual high value impedances for modifying and smoothing the direct current impulses.

Referring to Fig. 4 a lead 405 extends from the uppermost conductor of the line circuit ML to a direct current duplex equipment of conventional type, while at the opposite end of the line a lead 421 extends from the same line conductor to duplex equipment at 423 which may be in duplicate of the equipment served by the conductor 405. In a corresponding manner leads 406 and 422 connect other similar direct current equipments to operate in full duplex on a ground return basis over the lowermost conductor of line ML.

A key 425 may control a pole changer relay 426 in establishing changes of polarity to the common or apex point of the duplex circuit formed of a polarized relay 427, the upper winding of which is connected through an artificial line AL to earth, while the lower winding is connected over the lead 405 to the line conductor. Equipment at 428 under control of the relay 427 serves for reception of signals originating at the distant equipment 423. So-called blocking condensers 429, 430 connected in the main line conductors intermediate the balancing coils 401, 402 and the telegraph branches 405, 406, 421 and 422, serve for confining the currents of the direct current telegraphs to the line section ML and excluding such direct currents from the alternating current equipments served by the balancing coils 401 and 402.

Heretofore it has been necessary to provide positive reactance in the branch leads to the telegraph equipments with additional reactances connected to serve as drainage paths

from the main line conductors to earth, in composite working. Such positive reactances with other negative or capacitive reactances also required in such circuits for delaying or reducing the abruptness of the rise and fall 70 of the telegraph impulses have the further undesirable effect of appreciably extending the time required for each impulse. This reduces the signalling rate or speed and therefore lowers the message capacity of the 75 direct current circuits. The drainage paths mentioned also absorb or deflect some of the energy of the alternating current channels. In composite working, a phenomenon commonly referred to as "Morse thump" is present and in general is the result of periodic surges manifested when a discharge may result from a maximum potential "build up" or charge having been accumulated in the networks formed by the composite circuits. 80 85

In the present invention advantage is taken of the immunity of the acceleration type relays to substantially the most abrupt rise and fall of direct current impulses, and also to severe surges in the form of 90 Morse thump which may arise in the composite circuits. Therefore, as shown in the drawing all series, and drainage, or leak, reactances have been dispensed with as unnecessary and each branch lead for 95 the telegraphic equipments comprise a plain conductor substantially of zero reactance, as the respective conductors 405, 406, 421 and 422. Absence of the reactances permits increase in speed of signalling on the direct current channels and therefore an increase 100 in the message capacity of these telegraphs.

The importance of the filtering characteristics of the present sensitive receiving devices of the alternating current channels, may be more fully realized by mentioning that ordinarily electrical filters for excluding all but a certain frequency relative to alternating currents, are usually inadequate to exclude the relatively slow moving Morse 110 thump surges or inductive effects arising in the direct current telegraph channels. Heretofore it has therefore been necessary to suppress such effects at the source as by the inductances above mentioned, or to accept the resulting amount of interference 115 on the alternating current portion of the composite circuits, it has also been difficult to protect or safeguard against extraneous effects due to irregularities in the leads or 120 circuits of power lines which may parallel the telegraph lines. By comparison, the acceleration type relays of the present system while ordinarily avoiding the necessity for electrical filters are unaffected by the various surge or inductive effects above 125 mentioned. Therefore the acceleration type relays may be said to serve as translating devices for relaying impulses in the alternating current channels, while also serving 130

as filters in excluding sharp current effects due to high speed direct current working on other channels of the same line, and from extraneous inductive effects.

5 Fig. 5 shows the manner in which a metallic Morse system may be composed with a "duplicated" line such as ML. The rectangle 501 represents sending and receiving equipment at a West office comprising 10 apparatus similar to that shown in Figs. 1, 2 and 3 as well as a balancing coil such as coil 401. Similarly rectangle 502 represents 15 similar sending and receiving apparatus at an East office. Relay 503 is the usual pole changing relay as employed in metallic Morse systems. Relay 504 is a double differentially wound polarized relay which is neutral to signals transmitted by key 505 but is responsive to incoming signals to 20 affect sounder 424 as well known in the art. Rectangle 506 represents metallic Morse equipment which may be in duplicate of that shown at the left-hand end of the line in Fig. 5.

25 In circuits having superimposed metallic direct current telegraphs as distinguished from ground return telegraphs, the potential of the batteries is purposely made low in order to prevent inductive interference. 30 In the present system, however, the filtering ability of the receiving devices of the alternating current portion of the system substantially avoids this potential limitation and renders it possible to employ batteries 35 of such potentials as may best meet the transmission requirements and further permits greater distances of transmission and less frequent use of telegraph repeater stations.

40 The operation of direct current telegraphs is well understood, therefore, further description of such portions of the equipments of Figs. 4 and 5 is believed to be unnecessary.

45 It may be pointed out that manual type transmitting keys, as 108, 245, 425, 505 and sounders 116, 211, 213, etc. have been shown and described more as a matter of convenience, any of the well known forms of automatic transmitters and receivers well known 50 in the art may therefore be substituted for the manual equipment in attaining higher transmission speeds without departing from the present invention.

55 From the description given it will be clear that the alternating current relays of the present system may be readily employed for repeating signals from a first to a second line section. The present disclosure is believed 60 to be sufficient to render this point readily understood without adding further to the drawings. Therefore, let it now be assumed that the circuit WL may constitute a first line section, working through the equipment 65 at the West office as a repeater station into

a second line section EL terminating at a second or remote station. By inserting a patching cord 115 to join the respective jacks adjacent the jacks 122 and 124 the loop circuit 102 will be connected in series with the 70 loop circuit 101. The key 201 should now be in its operated position for full duplex working of the terminating circuit, while the battery supply key 206 may be positioned to the right. From the descriptions 75 already given it will be obvious that impulses of alternating current originating at the transmitting equipments 367, 377 may traverse the line WL, effect response of the relay 304 which may in turn affect the relay 80 112 to set up changes of current polarity in the loop 102. This loop now being patched in series with the loop 101 such changes of polarity will also become effective in the latter loop to set up responses of the relay 85 106. Thereupon the current generating vibrator 311 will respond and permit the relay 106 to apply impulses of alternating current to the line section EL. The receiving equipments 361, 371 may respond in translating these impulses. Under this arrangement of the circuits, the loops R and S may continue connected with the loops 101 and 102 and therefore may be said to correspond 90 with intermediate or way stations at which 95 sounders 114 and 116 may respond under the through signalling just described. At the switchboard point, the polarized sounder 211 is connected from the armature of the relay 112 in a so-called leak circuit to 100 ground, while in a corresponding manner the polarized sounder 213 is connected from the armature of the break relay 109 to ground. Therefore these sounders may respond to the through impulses for monitoring 105 purposes at the switchboard which may now correspond with a repeater point. It may be pointed out that under the full duplex arrangement of the circuits of Figs. 1 and 2 the break relay 109 is without effect 110 except that it may respond in unison with the line relay 106, and control the sounder 213 which is then alone connected under control of the break relay.

115 The line sections WL and EL may be such as commonly employed for telephone circuits and may include the usual types of repeaters such as vacuum tube arrangements for repeating voice currents. By means of patching equipment (not shown) but well 120 understood in the telephone art the equipment of the alternating current telegraphs may be readily patched to circuits which may be employed interchangeably as telephone circuits. This is rendered possible owing to 125 the sensitivity of the "acceleration" type relays being such as to render them capable of responding to currents of the order and strengths of currents present in the line circuits under speech transmission.

130 When it may be desired to operate the ter-

minal circuits on the so-called "half-duplex" basis the key 201 is placed normal while the battery key 206 may remain in its right-hand position. A like setting of corresponding switches is made at the duplicate equipment 361, 371 at the distant station.

In the present assumed position of the switches, the armature of relay 112 will be connected to the apex of the polar duplex circuit at the windings of current meter 110, while the spacing contact of the relay 112 will now be supplied with energy from grounded positive battery by way of jack 208, lower right contacts of key 206, conductor 255, marking contact and armature of break relay 109, conductor 155, contacts of key 201, thence over conductor 255 to the spacing contact of this West receiving relay 112. Energy for the marking contact of the relay 112 is now from negative grounded battery by way of jack 209, upper right alternate contacts of key 206 and conductor 154.

Alternating current impulses over line WL effect response of relay 304, and in turn relay 112 whereby the latter relay may effect changes of current polarity at the apex of the duplex equipment formed by the relays 106 and 109. As well understood in the art, although the net result of such current changes may be without effect on these relays, impulses may however be set up in the line loops 101 and S the circuits of which have already been traced, to effect operation of the receiving device 116.

Assuming now that an operator at the latter point may desire to "break" relative to the incoming signals, the key 108 may be opened preparatory to sending. This disconnection of the loop circuit 101 permits the armatures of the relays 106 and 109 to move to their spacing contacts. At the break relay 109 this switches the spacing contact of the relay 112 from positive to negative battery thereby rendering the latter relay ineffective since negative battery will now be present on both stops of this relay 112. At this time the spacing position of the relay 106 effects release of relay 331 and response of the vibrator 311 to energize the line EL with current at frequency f^5 . Due to the relay 112 having been rendered ineffective by the break relay as just described, impulses arriving from the East station may not be repeated back by the relay 106 over the circuit EL to work the home sounder at the sending operator's set. This immediate silencing of the latter sounder indicates the presence of the break signal to the operator originally sending and therefore it is usual for the "breaking" operator to start sending immediately following opening of the key to establish the break or interruption.

It may be pointed out that except for the use of the break relay 109 as described, the

ability of the relay 112 to cause the relay 106 to repeat the signals of the sending operator back over the circuit EL to the originating point would ordinarily delay recognition of the break signal which may only be indicated by mutilation of the returning signals due to manipulation of the key, at the set where the break signal may have originated.

At the switchboard the sounders 211 and 213 serve as already described for indicating signals which may be affecting the relays 112 and 106 respectively. In association with the sounders a telegraph key 215 may be employed for sending simultaneously into the telegraph loops 101 and 102. For this purpose, closure of a key 222 connects grounded battery over the winding of relay 111 to ground through the normally closed contacts of the key 215. As already traced, the left normal contacts of this relay are in series with the loop 101, while the right normal contacts are in the loop 102. It will therefore be obvious that under control of the key 215 the relay 111 may disconnect and connect the loops 101 and 102, to operate the sounders 116, 114 and the line relay 106. In these operations the relay 111 substitutes for the relay 112 relative to control of the loop 102, and also substitutes for the key 108 in controlling the loop 101. The responses of the relay 106 control transmission of alternating current impulses over the line EL in a manner similar to that already described. By operating the key 207 to the right, its lower contacts place a shunt on the left normal contacts of the relay 111. This shunting of the left contacts of the relay 111 confines control of this relay to the loop 102, the loop 101 and duplex relay 106 not then being affected by operation of the key 215.

The upper right contact group of the key 207 also transfers the circuit of the loop 102 from the armature of the relay 112 directly to grounded negative battery at the jack 209, thereby disabling the relay 112 relative to the present assumed sending into the loop 102 to work the sounder 114. It will be noted that the alternate contact of the right-hand armature of the relay 111 is connected by way of the lower right contacts of key 206 directly to positive battery at the jack 208. This permits the right armature of the relay 111 to serve as a pole changer in controlling a duplex equipment which may be patched to the jack 124 in substitution of the loop S. Such duplex equipment may be in duplicate of the present circuits shown in Figs. 1 and 2.

With the key 207 positioned to the left the loop 102 will be disconnected from the normal circuits to the relay 112 and connected by way of the upper right contacts of the key 206 to negative battery at the jack 209. This disables the loop 102 as may be

desired in monitoring operations, or during periods the key 201 may be set normal for half-duplex operation as already described.

The key 205 serves with the loop 101 substantially in the same manner as that just described relative to the key 207 and the loop 102. With key 205 to the right the circuit of the loop 102 is switched from the armature of the relay 111 to the routing previously traced to the armature of the relay 112. This renders the loop 102 independent of the relay 111 while the key 215 may work the relay 111 in interrupting the loop 101 to affect the sounder 116 and the relay 106 as already described.

With the key 205 positioned to the left, the upper transfer contacts switch the line path of the duplex equipment (relays 106 and 109) by way of the key 206 to positive 20 battery at the jack 208. The middle left transfer contacts of the key 205 switch the loop 101 by way of the upper right contacts of the key 206 to negative battery at the jack 209, while the lower left transfer contacts of the key 205 serve the same as the right-hand contacts of the latter key in switching the loop 102 from control by the relay 111 directly to the control of the relay 112, as already described. The loop 101 30 will now stand disabled while the relay 111 under control of the key 215 may effect responses of the relay 106 for sending over the line EL alone as hereinbefore described.

The battery key 206 has two positions so 35 that it may serve as a polarity reversing key in connecting battery of either polarity to the marking and spacing contacts of the relays 112 and 109. When positioned to the left the positive battery at jack 208 is connected to the spacing contact of the relay 109 and to the marking contact of relay 112, while the negative battery at jack 209 is connected to the marking contact of the relay 109 whence it may reach the spacing 40 contact of the relay 112. This polarity relation is inverse to that present when the key 206 may be positioned to the right as already described. Other contacts on the key 206 switch the terminals of the polarized 45 monitoring sounders 211 and 213 so that the marking and spacing effects will be in the proper positions for either polarity of the main batteries.

The key 203 serves for reversing the real 50 line side with the artificial line side of the duplex equipment (relays 106 and 109) and is more particularly for situations where the upper lead of the circuit 101 may be patched to a line conductor forming a ground return circuit at the distant end of which duplex equipment similar to the equipment of Figs. 1 and 2 may be present. The main battery switch 206 is also concerned in such 55 an arrangement which chiefly affects the polarities of the main line batteries in afford-

ing an accumulative effect relative to the energy supplied from the two terminals of a line and also the matter of the biasing direction of the polar relays in order that engagement with the spacing and marking contacts of the relays may be in the proper order at both points. For example, assuming that equipment similar to that of Figs. 1 and 2 may be present at the East terminal of a ground return duplexed line formed of 70 the upper conductor of the loop 101, the key 206 being positioned to the right, the key 203 normal, the key 201 to the right for full duplex operation and the patching cord 115 connected in joining jack 124 with the jack 202, the armature of the relay 112 will thus be connected to the apex of the duplex circuit at the meter 110 in substitution of negative battery over the "cut-off" contacts of the jack 202. At the West point, on this assumed line, corresponding key 206 will be positioned to the left, key 203 operated and key 201 will be operated to the right for full duplex working at the latter point. In this position of the circuits the control points of 80 the break relays 109 at each point will be rendered "ineffective" as already described. The normally closed or marking contact of the relay 112 will be energized by negative 85 battery from the jack 209 while the spacing contacts of this relay will be energized from positive battery at the jack 208. Therefore negative grounded battery will normally be present to the duplex equipment to continue 90 outward over the assumed line. Due to the inverse positions of the switches 206 and 203 at the assumed West office, positive grounded battery over the marking contact and armature of a relay corresponding with the relay 112 may flow through the duplex circuit 95 to line in meeting the negative current from the East office. Negative battery will be present on the spacing contact of the latter relay while the inverse relation of the windings of the relay 106 at the West office due 100 to the operated position of the associated key 203 will correct for the condition of positive battery normally at the apex of the duplex equipment. Therefore, correction of bias 105 will thus be established and the armature 110 of the relay 106 at the West office will normally stand in proper position on its marking contact.

For the last assumed circuit condition it 115 will be obvious that impulses of alternating current over the line WL may control the relays 304 and 112 to repeat direct current impulses into the direct current duplex circuit, whence at the distant assumed West office a relay corresponding with the relay 106 may control alternating current equipment 120 similar to the equipment T¹ in retranslating the direct current signals into alternating current signals for transmission over 125 a circuit similar to the circuit EL. In a 130

converse manner from the West office impulses may simultaneously be impressed over the full duplex line to be translated therefrom by the relay 106.

5. It may be mentioned that for line patching as just described, the upper conductors of the loops 101 and 102 are usually provided with jacks not shown but which may be present at the broken line points. This 10 eliminates the call signal relays 113 and 119 from the circuits when thus patched.

To call the operator or repeater attendant from the loop S, operation of a key 118 applies ground potential substantially to shunt 15 the left-hand winding of the relay 113. Thereupon this differential relay responds to the larger current in its right-hand winding and applies grounded battery through the winding of relays 121 and 216 to ground 20 through a key 217. The relay 121 locks itself and the relay 216 independently of the relay 113. Response of relay 216 closes obvious circuits to energize signal lamps 218, 219 and also a circuit to sound an audible 25 signal 221. In responding to such a call the attendant may momentarily depress key 217 to release the relays 121 and 216 and thereby restore the signals 218, 210 and 221, set the key 207 to the left, close the switch 222 and 30 operate key 215 to work the sounder 116 as already described.

At the switchboard, keys 212 and 214 respectively serve for disconnecting the sounders 212 and 213 when desired, jacks 35 208, 209 serve for testing and patching; while the jacks respectively in association with jacks 122 and 124 may be patched to additional loops equipped similar to the loops S and R. Resistances 172, 174 and condenser 173 and the second group of similar units serve as protection against sparking at the contacts of the relays 109 and 112. This in conjunction with the impedance coil 171 for modifying the impulses relative to 40 the controls of these relays.

45 What is claimed is:

1. The combination in a telegraph system of a transmission line, means for simultaneously impressing on said line a plurality of alternating currents of different frequencies, means under control of message signals for correspondingly changing the character of said alternating currents, receiving devices for said changed currents 50 each comprising a contact set, and a vibratory circuit controlling member for engaging said contact set, said member being adapted when in vibration to exert continuously one condition of circuit control over said contact set and to exert continuously when at rest another condition of circuit control to give rise to direct current message impulses corresponding to said message signals.

65 2. The combination in a telegraph system

of a transmission line, means for impressing on said line a plurality of alternating currents of different frequencies, means for modulating said currents in accordance with message signals, receiving devices each comprising a direct current circuit and an electromagnetic mechanism having a member tuned to selectively respond to a given frequency, each member serving normally to maintain the associated direct current circuit continuously in a given condition and vibrating in response to the currents of the frequency to which it is tuned to continuously maintain the said associated circuit in another condition to give rise to direct current message impulses. 70

2. The combination in a telegraph system of a transmission line, means for simultaneously impressing on said line a plurality of carrier currents of different frequencies, means for modulating each of said currents in accordance with direct current message impulses, a plurality of receiving devices each selectively responsive to a particular one of said carrier currents and carrying a vibrating member, said member continuously vibrating when said carrier current is unmodulated and continuously at rest when said carrier is modulated by message impulses, a direct current receiving circuit for each device and means for normally maintaining said circuit continuously in one condition when the associated device is at rest and continuously in another condition when the associated device is vibrating. 80

3. The combination in a telegraph system of a transmission line, means for simultaneously impressing on said line a plurality of carrier currents of different frequencies within the voice range, receiving means for each carrier current comprising a vibratory relay and a direct current circuit, said vibratory relay having a movable member and contacts associated with said direct current circuit, means effective under one class of signals for applying uninterrupted carrier current to said line to maintain the movable member of the associated relay continuously vibrating and for maintaining the associated direct current circuit continuously in one condition, and means effective under a different class of signal for interrupting said carrier current to maintain said movable member at rest and to correspondingly maintain the associated direct current circuit continuously in another condition. 90

4. The combination in a signalling system of a transmission line, means for simultaneously impressing on said line carrier currents of the order of speech frequency, a receiving device for each carrier current comprising a vibratory member and a set of contacts adapted to complete a direct current circuit when said member is at rest 100

- and to continuously open said circuit when said member is vibrating, means for controlling the application of modulated carrier currents to said line in accordance with 5 direct current message signals, said modulated currents adapted when so applied to maintain the associated receiving devices continuously at rest, and means for controlling the application of unmodulated carrier currents to said line in accordance with 10 direct current message signals, said unmodulated currents adapted to maintain the associated devices in vibration.
6. In a telegraph system, the combination 15 of a line comprising direct current and alternating current sections, a vibrator for converting direct current into alternating current in relaying signals between said line sections, and an acceleration type relay for 20 translating signals received from said alternating current line section.
7. In a telegraph system, the combination 25 of a line comprising direct current and alternating current sections, a vibrator of the short-circuiting type for converting direct current into alternating current in relaying signals between said line sections, and a vibratory type relay for translating signals received from said alternating current line 30 section.
8. In a telegraph system, the combination 35 of a line comprising direct current and alternating current sections, a vibrator of the short-circuiting type for converting direct current into alternating current in relaying signals between said line sections, and an acceleration type relay for translating signals received from said alternating current line section.
9. In a signalling system utilizing signal currents at low potential levels for prevention of interference between different portions of the system, short-circuiting vibrators for producing signalling currents, transmitting devices for applying said currents to said line, and acceleration type relays for 45 selectively receiving said currents.
10. In a system of combined alternating 50 current telegraphy and telephony, a line including repeaters for use interchangeably for speech transmission and for telegraphic transmission, short-circuiting vibrators for producing signalling energy of the order of speech currents, transmitting means for applying said energy to said line for signalling, and acceleration type relays for reception 55 of said energy.
11. In a telegraph system, a line providing a plurality of alternating current channels and a plurality of direct current channels, transmitting and receiving equipment for each of said channels, a short-circuiting vibrator for each alternating current channel for producing signalling energy for said 60 channel, and means responsive to the condi- tion of the transmitting equipment associated with an alternating current channel for effecting the operation of the associated vibrator.
12. In a telegraph system, the combination 70 of a line comprising direct current and alternating current sections, a short-circuiting vibrator for supplying carrier current of voice frequency to said alternating current circuit, said vibrator being normally inert when no messages are being sent over 75 said direct current section, means effective when message impulses are about to be sent over said line for causing said vibrator to operate to apply carrier current thereto, means for modulating said carrier current in accordance with direct current message impulses, and receiving relays for directly converting the modulated current into corresponding direct current message impulses. 80
13. In a system of alternating current telegraphy, a plurality of message channels, a pilot channel for said message channels, and means operative during signal transmission on any of said message channel for disabling 90 said pilot channel.
14. In a system of alternating current telegraphy, message channels, a pilot current channel for said message channels, a source of alternating current and receiving means 95 for said pilot channel, and means for disabling said source of pilot current when signals are present on any of said message channels.
15. In a telegraph system, the combination 100 of a plurality of sending channels, a main line for simultaneously propagating messages received from a plurality of said channels, a source of current for piloting said main line, means for applying said 105 piloting current to said line when said line is idle, and means for disconnecting the piloting current from said line when messages are being sent over any of said channels. 110
16. In a system of alternating current telegraphy, a line for providing a plurality of message channels, sources of alternating currents, transmitting devices for applying said currents to said line only when signalling 115 thereover, a source of pilot current, and means responsive to an inert condition of said devices for applying said pilot current to said line. 120
17. In a system of alternating current telegraphy, a line for providing a plurality of signalling channels, equipment for a first channel to indicate the condition of said line, signalling equipment for a plurality of other channels, and means responsive to an inert condition of said signalling equipments for rendering the equipment of said first channel effective. 125
18. In a telegraph system, the combination 130 of a main line, message channels con-

neected with said main line, a pilot channel and a source of current therefor, means effective when said line is not in use for connecting pilot current thereto to give a continuous indication of the condition of said line, and means effective when any of said channels are in use for disconnecting the pilot current from said line.

19. In a telegraph system, the combination 10 of a main line, message channels connected with said main line, sources of carrier currents for said message channels, a pilot channel and a source of current therefor, means effective when said line is not in use for connecting pilot current thereto, and means effective when any of said channels are in use for replacing said pilot current by a carrier current.

20. The combination in a system of alternating current telegraphy of a main line, 20 telegraph message channels connected with said main line, a pilot channel and a source of current therefor, receiving means for said pilot current comprising a relay for directly 25 converting said pilot current into a continuous current indication, said receiving means being effective when the main line is not in use.

21. The combination in a system of alternating current telegraphy, of a main line, a 30 plurality of message channels connected with said line, a pilot channel for said line, a short-circuiting vibrator common to all of said message channels for supplying pilot current to said pilot channel, means effective when all of said message channels are idle for rendering said pilot channel effective to give a continuous indication of the condition of the main line, and means effective when 40 any of said channels is in use for replacing said pilot current by carrier current.

22. In a telegraph system, a line for providing a plurality of alternating current and direct current message channels and a pilot 45 current channel, said line being energized by signalling energy only when one of said message channels is in use, supervisory means including indicators for showing a busy condition of said message channels 50 adapted to automatically energize said pilot current channel when all of said message channels are idle, and means for rendering said pilot current channel effective to control a predetermined one of said indicators.

55. 23. In a telegraph system, a line, a plurality of alternating current message channels, a plurality of direct current message channels, and acceleration type relays for excluding from said alternating current 60 channels current effects of said direct current channels while translating signals in said alternating current channels.

24. In a telegraph system, a line adapted 65 to propagate alternating current telegraph signals simultaneously in both directions,

means for impressing said signals on said line, and means for superposing on said signals unmodified high speed direct current telegraph signals, said alternating current signals and said direct current signals being propagated over said line without mutual interference.

25. In a telegraph system, a line adapted 75 to propagate alternating current telegraph signals simultaneously in both directions, means for impressing said signals on said line, high speed direct current telegraph equipment, and means comprising a circuit of substantially zero impedance for operatively associating with said line said high speed equipment whereby unmodified direct current telegraph signal impulses may be impressed on said line without interference with said alternating current signals.

26. The combination in a telegraph system, of a main line adapted to simultaneously propagate alternating current signals and direct current signals without interference, a plurality of sending devices 80 for impressing alternating current signals on said line, a plurality of sending devices for impressing direct current signals on said line, a plurality of receiving devices for receiving said direct current signals, and means comprising circuits of low electrical 85 impedance for operatively associating said second mentioned sending and receiving devices with said line.

27. In a telegraph system, a main line 90 adapted to simultaneously propagate alternating current signals and direct current signals, means for impressing on said line carrier currents within the voice frequency range, means for modifying said carrier currents in accordance with direct current telegraphic signals, and a circuit of substantially zero impedance for associating direct current telegraph signalling apparatus with said line, whereby high-speed Morse signals 95 may be superposed on said modified currents without mutual interference.

28. In a telegraph system, a two-conductor line, alternating current duplex telegraph equipment for affording a plurality of alternating current signalling channels over said line, direct current duplex telegraph equipments connected to each conductor of said line through paths of substantially zero reactance, and acceleration type relays in said alternating current equipments serving as 105 receiving relays for alternating current signals, said relays being unresponsive to current effects in said direct current equipments.

29. In a telegraph system, a direct current 125 line section, duplex sending and receiving telegraphic equipment for said line section, an alternating current line section, duplex signalling equipment for said alternating current line section, short-circuiting vibrators 130

for producing signalling energy for said alternating current line sections, a second direct current line section, duplex sending and receiving equipment for said second line section, 5 means for translating signals from said direct current line sections into alternating current signals for said alternating current line section, and acceleration type relays for translating signals from the alternating current line section into signals for the direct current line sections.

30. In a telegraph system, a line providing a plurality of alternating current message channels and a plurality of direct current message channels, transmitting and receiving devices for said direct current channels for producing signalling impulses of sharp wave form, transmitting and receiving devices for said alternating current channels 15 comprising filters formed of acceleration type relays for translating signals in said alternating current channels while excluding current effects arising from said sharp wave signal impulses.

25 31. In a telegraph system, a first direct

current line section, a second direct current line section, duplex telegraph equipments for said line sections, a two conductor alternating current line section intermediate said direct current line sections, duplex signalling 30 equipment for said alternating current line section, other direct current duplex telegraph equipment superposed on said alternating current line section by circuits of substantially zero reactance and forming circuits 35 independent of the first and second line sections, means for translating signals from the first and second line sections into signals for the alternating current line sections, and acceleration type relays serving as filters in 40 eliminating current effects of said superposed equipments while said relays are translating signals from said alternating current line section into said first and said second line sections.

45 In witness whereof, I hereunto subscribe my name this 7th day of August, A. D., 1925.

HENRY W. O'NEILL.
